(57) **CLAIM**

The ornamental design for a front closure for a brassiere, as shown and described.

DESCRIPTION

FIG. 1 is a front elevational view of a front closure for a brassiere showing our new design;

FIG. 2 is a right side elevational view thereof, the left side elevational view being mirror symmetrical thereto;

FIG. 3 is a bottom plan view thereof, the top plan view being mirror symmetrical thereto;

FIG. 4 is a rear elevational view thereof;

FIG. 5 is a rear elevational view of one member thereof, separated from the other;

FIG. 6 is a left side elevational view of the member of FIG. 5;

FIG. 7 is a bottom view of the member of FIG. 5;

FIG. 8 is a front elevational view of the member of FIG. 5;

FIG. 9 is a rear elevational view of the other member;

FIG. 10 is a right side elevational view of the other member;

FIG. 11 is a bottom plan view of the other member; and,

FIG. 12 is a front elevational view of the other member.
